ROTARY PUMP

Francisco Angel Quiroz, Newark, N. J.

Application January 14, 1937, Serial No. 120,465

1 Claim. (Cl. 103—142)

My invention relates to rotary pumps suitable for pumping all kinds of liquids or gases or a mixture of a liquid and a gas.

One of the objects of this invention is to provide a pump highly efficient, simple in construction, reliable and inexpensive to manufacture.

Another object is to provide a rotary pump well balanced, with a minimum of rotary moving parts, mounted on a single shaft and suitable for high speed.

Another object is to provide a pump of the character described with means for by-passing a small quantity of the liquid in order to maintain a good seal between the rotary members and the stationary parts at all times, and make the pump self priming.

A further object is to provide a pump which can be easily altered in order to obtain different volumetric capacities with the same size of parts and at the same rotary speed.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claim.

In the accompanying drawing in which are shown a preferred form of various possible embodiments of the mechanical features of my invention,

Fig. 1 is a central vertical sectional view of the pump with part of the shaft shown in elevation.

Fig. 2 is a cross vertical sectional view along the line 2—2 of Figure 1.

Fig. 3 is a perspective view of the slotted shaft 4 with the flat member 5 held in position by pin 6.

Fig. 4 is a perspective view of the rotary member 3 shown in section in Figures 1 and 2.

Similar reference characters refer to similar parts throughout the several views in the drawing.

Referring now to the drawing the apparatus comprises a main casing 1 which is provided with a chamber 7 where the rotary members operate, an inlet port 8, an outlet port 9, a bearing housing 10, legs 11 and 12 and tap holes 13, for the bolts that secure the cover 2 in its place.

The cover 2 is provided with a bearing housing 15, which is concentric with the bearing housing 10 and supports the other end of the shaft 4. A cover 15a keeps the bearing in position and prevents the leaking of any fluid going through the bearing 16; said cover 15a is held in position by

bolts 17. Another cover 18 serves the same purpose as the cover 15, but it is provided with a stuffing box 19, and a gland 20, to allow the driving end of the shaft 4 to go through.

The shaft 4 is provided with a slot 21 which is practically of the same width as the flat member 5, at the center where said member 5 is pinned to said shaft, but said slot widens out at both ends to allow the flat member 5 to oscillate back and forth as the shaft 4 is rotated. The flat member 5 is practically a rectangular member with one of the narrow sides 22 slightly round making an arc with a height equal to the height of an angle made by two lines having an inclination equal in degrees as the oblique end of the casing has to the perpendicular end of the same, and a base equal to the width of the propeller member, 5. To conform with this round face of the flat member 5, the face 23 of the slot is also round in the same proportion, in order to prevent any leakage of the fluid from one side to the other, while the member 5 oscillates.

The ends of the flat member 5 are slightly curved making an arc with a radius having the center at the center of the pin 6 as the starting point.

The rotary member or rotor 3 is a circular disc with one straight face 25a and one conical face 26 of approximately the same diameter as the circular chamber 7 to have a slide fit therein, and has a hub 24 extending from the straight face 25a. The conical face 26a has the same angle as the inner face 26 of part 2, and when in place, fills entirely the space of the upper part of chamber 7. An axial hole 27 runs across the hub 24 and the center of the disc 3. A slot 30 runs diametrically across the conical disc 3 and the hole 27, leaving only two steps 28 and 29, which serve as a stop for the flat member 5 as shown in Figure 1.

The conical disc 3 is firmly secured to the shaft 4, preferably by a pin 31, practically making the disc an integral part of the shaft 4.

It can be clearly seen that the flat surface of the disc 3, fits closely to the ribs 32 and 33. These ribs are formed in the main casing, 1, and are an integral part of the same. They are slightly wider than the slot 30 in the rotor 3, in order to make a good seal, but they are not too wide to interfere with the liquid by-passed in the slot 30, which is used to prime the pump, but there is a space as shown by dotted line 34 in Fig. 1 between the disc 3 and the casing 1, in order to allow the fluid to get in and out of the groove 30, when the flat

member 5 oscillates in and out of said groove 30, as it is shown at 7 in Fig. 1.

The inclined surface 26 of the cover 2 is built with the same angle of the conical surface of disc 3, and fits closely to the upper side of the disc, preventing the passage of liquid from the pressure side 36 to the suction side 37, but leaves an opening at the lower side, as shown in 38, which space is of the same cross sectional area as the protruding end of the flat member 5, therefor each end of said member 5, works as a rotary piston in said space 38, forcing the fluid that gets into said passage 38, from one side to the other, depending on the direction of rotation of the shaft 4. Another small amount of fluid is passed by the empty space of the groove 30.

As it can be clearly seen this pump is reversible, and either one of the ports 8 or 9 can be the suction or the discharge port.

20 This pump is self priming due to the fact that a small quantity of liquid is left at all times inside of the pump's main chamber, and it is by-passed by the groove 30 from one side to the other, sealing the clearance between the different parts and 25 producing a good vacuum at the suction side.

The operation of this pump is the same as the operation of an ordinary rotary pump of the blade type, but has the advantage of preventing a radial thrust against the periphery of the casing, and 30 preventing the fluid in the back of the blades from being squeezed between the parts. Another advantage is that the blades rotate at a constant speed, which is not the case with the eccentric rotary radial blades.

35 As many possible embodiments may be made of the above invention and as many changes might be made in the embodiment set forth, it is to be understood that all matter hereinbefore set forth or shown in the accompanying drawing is 40 to be interpreted as illustrative and not in a limiting sense.

I claim:

In a rotary pump of the character described in combination a casing having a cylindrical pump chamber therein, said chamber having a perpendicular wall at one end thereof, a wall extending obliquely to the chamber axis at the other end thereof, and a cylindrical wall joining said end walls, said perpendicular wall being provided with a diametrical raised portion extending into the chamber and forming a rib, a fluid inlet port in the cylindrical wall of the chamber extending from one end and side of said rib, a fluid outlet port in the cylindrical wall of the chamber extending from the same end but opposite side of said rib and in the opposite direction from said inlet port, said perpendicular wall and rib having a central bore extending therethrough, a shaft rotatably mounted in said bore and extending into said chamber, a rotor of the same diameter as said chamber fixedly mounted on said shaft within said chamber, said rotor having three faces, one face perpendicular to its axis and the opposite face thereof conical, the third face thereof being cylindrical and joining said other two faces, the perpendicular rotor face being mounted in close contact along the entire rotor diameter 20 with the said rib, the conical rotor face being in close contact with a radial line of the oblique end of the chamber, said rotor having a diametrical slot therein extending throughout the length of the rotor and of a width slightly less than the 30 width of the rib, and a fluid impelling blade of the same width as the slot mounted in said rotor slot to oscillate toward and from the chamber end walls, said blade being so mounted as to have constant contact at one side with the oblique end 35 wall during rotor rotation and to provide a space in the rotor slot at the end thereof adjacent the perpendicular chamber end wall, said space being open to fluid pressures in the pump chamber except when said slot is opposite the rib. 40

FRANCISCO ANGEL QUIROZ.
